UNITED STATES PATENT OFFICE

EDWARD KARFIOL, OF NEW YORK, N. Y.

SHELF PAPER

Application filed April 30, 1932. Serial No. 608,379.

This invention relates to shelf papers and is inclusive not only of those which are used as a shelf covering and are provided with edgings adapted to hang over the front edge 5 of the shelf, but to shelf papers which constitute edgings only.

Both shelf papers with edgings and edgings per se for use on shelves have long been employed and in recent times the edgings in particular have been scalloped, picoted, denticated or otherwise conformed, while the surfaces of the edgings have been embossed, printed and otherwise decorated to produce æsthetic designs in shape and color.

15 Shelf papers and edgings as required by the trade necessitate the use of economical stock and manufacturing prices must be kept at a minimum, while the requirements for the æsthetic steadily increase. The paper here- 20 tofore employed has, generally speaking, been of a relatively cheap texture, well adapted for ornamentation and design and permitting it to readily conform to the shelves and/or the front edges thereof. This paper is eco- 25 nomically manipulated in the course of manu- facture and effectually serves its purpose from the standpoint of service, wear and appearance. It is open, however, to the serious 30 objection that it requires careful handling and tends to tear at the edges when subjected to relatively slight tensional strains or when struck by articles during placement on or removal from the shelf.

Furthermore shelf papers with edgings and 35 edgings alone are generally packaged in rolled or in longitudinally folded condition. When such packages are opened and the paper strip applied to the shelf, there is a 40 tendency in all papers now manufactured to bulge or hang from the edge of the shelf in a wavy, unattractive manner, whereas for the best artistic effects, the edging should hang sheer, in a straight line. One of the most 45 difficult problems in this art is to make a shelf paper which will hang sheer, as specified, which will not crimp or bulge and which will present a neat and tailored appearance.

With the foregoing considerations in mind, 50 the object of the present invention is to pro- vide a shelf paper with associated edging or

an edging per se which will be free from the disadvantages to which I have referred, namely, one which will hang sheer and will present a tailored appearance and at the same time will be sufficiently strong to better withstand all ordinary strains to which paper of the character specified will be normally subjected.

Another object of the invention is to produce a shelf paper where a number of new and 55 attractive designs may be made or formed by the use of combinations of colored, plain, pleated or embossed reinforcing members.

Another object of the invention is to produce a shelf paper where the face of the shelf 60 paper is made of a high grade stock and the main portion may be made of a comparatively 65 inferior grade.

And still another object of the invention is to produce a laminated or reinforced shelf 70 paper in which the laminations run parallel with the outer edge of the paper at predetermined distances from the outer edge thereof, and extends transversely of the shelf paper 75 to a depth of the face or the embossed or printed portion thereof slightly overlapping same. A shelf paper that is inexpensive to manufacture and at the same time being very strong, ornamental and attractive.

Speaking generally, the invention consists 80 in providing paper edging with longitudinal reinforcing members, preferably in the form of bands which extend longitudinally of the shelf edge when the edging is in place there- 85 on. These longitudinal reinforcing bands extend parallel to the line of symmetry of the lower free edge of the edging and form an inherent part thereof, the several parts of said edging being permanently united to one another in a manner to effect maximum 90 rigidity and strength. The incorporation of such longitudinal reinforcing means mini- 95 mizes the tendency of the edging to flare or present a wavy, unsightly appearance and, at the same time, imparts to such edging increased strength, permitting it to withstand such tearing strains to which it would ordinarily be subjected.

An important feature of the invention is 100 inherent in the fact that the reinforcing bands

to which I have referred may be so disposed as to materially reinforce that portion of the edging which extends over the forward upper edge of the shelf, so that when the shelf paper, for example, is folded down over the edge of the shelf, it will not tend to break, tear or curl.

Features of the invention, other than those adverted to, will be apparent from the hereinafter detailed description and claims, when read in conjunction with the accompanying drawings.

The accompanying drawings illustrate different practical embodiments of the invention, but the structures shown therein are to be understood as illustrative, only, and not as defining the limits of the invention.

Figure 1 is a fragmental section perspective showing a portion of the shelf with the shelf paper positioned thereon and provided with an edging embodying this invention.

Figures 2, 3, 4, 5, 6, 7, 8 and 9 are similar views showing illustrative, modified forms of the invention.

Figure 10 is a view similar to Figures 1-9, but showing a shelf edging of this invention.

Figures 11 and 12 are sectional views similar to Figure 10, but showing further modified forms of the invention incorporated in the edging only.

Shelf papers with shelf covering portions and edgings are conveniently manufactured in the form of paper strips of various widths and lengths appropriate for use on shelves of corresponding dimensions. In the several figures of the drawings, I have indicated a shelf by the reference character 1, the forward edge of said shelf being designated 2. The shelf covering portion of the shelf paper strip is designated 3 and embodies that portion of the paper strip which actually overlies the upper surface of the shelf.

By reference to Figure 1, it will be noted that, at the forward margin of the shelf covering portion 3, a flap 4 is adapted to hang free over the front edge 2 of the shelf and form an edging therefor. It is this flap which, in practice, tends to curl, bulge and assume a wavy appearance which detracts from the appearance of the edging. Furthermore, it is this flap which, under present practice, becomes easily torn or damaged.

The present invention so far as shelf papers are concerned are directed to improvements in this flap for the purpose of strengthening the same and to insure a neat, tailored appearance thereto.

According to the invention as exhibited in Figure 1, there is attached to the flap one or more reinforcing bands. In this figure, two such bands 5 and 6 are shown, one of which is placed on the front or exposed face of the flap and the other of which is positioned on the back or concealed face of the flap. In practice, either of said bands may be omitted

so that the flap has either an inside band or an outside band as desired, but through the employment of a double band greatly increased strength and rigidity are obtained. The bands 5 and 6 are of paper and may be made of the same paper as the shelf covering portions and flaps 3 and 4, or they may be made of an inferior or superior paper as may be desired.

The reinforcing bands described and shown in connection with Figure 1 of the drawings, as well as the reinforcing bands and members, which I will hereinafter refer to in connection with the remaining figures of the drawings, are secured to the flap in a permanent manner by any one or more of several methods which serve to "adhesively" maintain the parts in assembled relation. The term "adhesively", as used throughout this specification, is defined as that relation or state which causes the parts to adhere or be affixed to one another by adhesion and to be joined or united. This adhesion may be brought about as stated in several ways.

For example, the parts may be caused to adhere to one another by applying to one or both of them a paste or glue which will cause said parts, when brought together, to stick to one another by virtue of the interposed cementitious material.

By way of further example, the adhesion to which I refer may be obtained by moistening or dampening the paper plies and forcing them together under pressure with or without the presence of heat to cause them to adhere to one another through their own inherent properties of adhesion.

By way of further example, the parts may be placed in face abutting relation to one another and pressed, embossed, punched, or otherwise manipulated to cause the fibres or different parts of the several laminations to interfit or interlock in a manner to cause said parts to adhere to one another and possess the property of mutual adhesion.

Thus, the adhesive relation to which I have and shall refer contemplates generically the act or state of adhering or of being united and attached in close connection or association by the inherent properties of the materials of the respective parts and/or through the manipulation of said parts and/or the interposition of a cementitious material or glue between the parts.

If a cementitious material or glue is employed to adhesively secure the parts together, I find in practice that in certain combinations of papers best results are obtained if the glue or paste is applied to one or both of the parts to be secured together by broadcast distribution over said surface or surfaces, while other combinations of paper appear to best advantage if they adhere only at certain points which may be regularly or irregularly spaced. Thus, when the parts are adhesively

secured together by glue or otherwise, they may be secured together throughout their respective extents or at isolated localities which may be regularly or irregularly spaced apart.

5 Furthermore, if glue or other cementitious material is employed, it is possible to perforate that portion of the flap which lies between the bands 5 and 6, so the cementitious material applied to one of the bands will pass 10 through the perforations of the flap and thus be applied to the other band when the parts are brought together for the purpose of securing all three parts together.

It will be noted from Figure 1 that the 15 finished product has an edge which is materially reinforced through a laminated arrangement of paper plies adhesively secured together and for the purpose of illustration in this and the other figures of the drawings,

20 I have shown the parts as glued together by a cementitious material, indicated at 7, without, however, intending to restrict the invention to the use of such material to obtain the adhesive relation to which I have referred.

25 When a laminated arrangement is produced, as shown in Figure 1, the resulting structure will have an edge which is materially reinforced and stiffened with the result that when shelf paper of this character 30 is applied to a shelf the tendency of the edge to curl or bend is minimized and a smooth, tailored appearance results.

In the structure of Figure 2, the reinforcing band 8 is applied in the same manner 35 as the band 5 in Figure 1, but is of such transverse width that it extends from the lower free edge of the flap 4 upwardly to cover the entire flap and extend over the adjacent margin of the shelf covering portion 3 as shown at 9. It is adhesively secured 40 to the flap and the part 3 and entirely conceals the flap when the shelf paper is in place on the shelf. The arrangement shown in this figure permits of the employment of an inferior grade of shelf paper for the parts 3 and 4, since they are entirely concealed, while 45 the paper band 8 may be of a high grade paper.

If desired, the structure of Figure 2 may 50 be reversed, that is to say, the reinforcing band 8 may be adhesively secured to the back side or concealed face of the flap 4. In either event, the laminated reinforcing stiffening effect of the band 8 will be very material in 55 this construction.

The structure of Figure 3 is similar to that of Figure 2 except that the reinforcing band 8 is of a less width than the flap 4, so as to expose the lower portion of the flap and said 60 band also terminates at the upper edge of the edging and does not extend over the margin of the part 3 which rests on the top of the shelf. This arrangement does not provide for a reinforcing of the band at the junction between 65 the edging and the shelf covering por-

tion 3. I wish it here understood that the reinforcing of this line is not essential to the invention and may be eliminated in any of the figures of the drawings where it is shown without departing from the invention. 70

Figure 4 exhibits a modified form of the invention. Here instead of positioning the reinforcing band along the lower free edge of the flap 4 or extending it for the full width of the flap as in Figure 2, a plurality of reinforcing bands 10 and 11 are vertically spaced apart from the edge of the flap and from each other. Any number of these bands may be employed and they may have ornamental edges if desired and be positioned on either 80 or both sides of the flap depending upon conditions. They may be made of different paper from that embodied in the flap 4 or from each other.

In the structure of the preceding figures, 85 the reinforcing bands may be adhesively secured to the flap 3 throughout their entire widths. In Figure 5, however, two reinforcing bands 12 and 13 are shown, both of different width with respect to one another and 90 with respect to the flap 4. Portions of the width of both bands are secured to the underlying part, but the free edges of the bands as well as the free edge of the flap are unattached. The band 12 is secured to the flap 95 4 from the line 14 to its upper edge, while the band 13 is secured to the band 12 from the line 15 to its upper edge. Thus, different transverse portions of the flap are reinforced by one and two additional reinforcing bands, 100 respectively, while the free edge of each of these parts is unattached, so as to hang unattached and produce a deeper shadow at the lower edges of the bands 12 and 13, while at the same time reinforcing the flap 4 as hereinbefore described. 105

The arrangement of Figure 5 furthermore reinforces that portion of the shelf paper which extends over the shelf edge of the shelf, against tearing at this line. 110

The structure of Figure 6 is, in many respects, similar to the structure of Figure 5, except that the two reinforcing bands 16 and 17 are positioned back of the flap 4 and are secured thereto and to one another, as 115 shown, to produce a longitudinal reinforced edging and to likewise reinforce the shelf paper at the shelf edge.

The arrangement shown in Figure 7 is in many respects similar to that of Figure 6, 120 except that the rearmost reinforcing band 18 which corresponds to the band 17 does not extend to overlie the edge of the shelf, but terminates short of the band 16 a distance somewhat greater than the thickness of the 125 shelf. In this construction, there is effectual longitudinal stiffening with less reinforcement at the edge of the shelf and with corresponding saving of paper stock.

Figure 8 shows a further illustrative form 130

of the invention as applied to shelf papers. Here the flap is made relatively short and two reinforcing bands 19 and 20 are shown adhesively secured to the flap, so that when the paper is on the shelf, the reinforcing bands will hang below the lower edge of the flap. In practice, I may use two reinforcing bands 19 and 20 as shown, which bands may be of the same widths or different widths as illustrated, or I may use either of these bands to the exclusion of the other without departing from this invention. A very satisfactory structure results if the flap is provided with only one reinforcing band 19, for the reason that this structure produces marked economies by minimizing the width of the shelf covering portion and flap due to the relatively narrow width of the flap in this figure.

In the several preceding figures of the drawings, the reinforcing bands are shown in each instance as made separate from the flap 4 and thereafter secured thereto. It is possible, however, to obtain a satisfactory arrangement by making the so-called reinforcing bands integral with one another and with the flap 4 as shown in Figure 9. Here the flap 4 is made much wider than the finished edging and is transversely pleated with one or more close overlying pleats as shown in this figure, so that, in effect, the flap 4 is reinforced by integral laminated bands 22 and 23 which are adhesively united therewith to produce a three ply laminated reinforced structure, while, in turn, the lower edge of the band 23 is pleated and reinforced by the bands 24 and 25 which are adhesively secured together as will be understood to provide a three ply laminated stiffening reinforcement.

The parts shown in Figure 9 are all integral with one another, but they may be made separate and united as in the preceding figures instead of produced by pleating as described. However, irrespective of the method of making, there are present in Figure 9, the reinforcing bands functioning to longitudinally stiffen the edging of the shelf paper as in the preceding figures.

In Figures 1 to 9 of the drawings, the edging forms part of, or is associated with, a shelf covering portion 3 adapted to overlie the upper surface of the shelf. The present invention is, as hereinbefore stated, not limited to the inclusion of the portion 3, but may be incorporated in shelf edgings, which do not have a shelf covering portion or are associated with independent shelf coverings.

In Figure 10, I have shown the general structure of Figure 5 adapted to edging, this being accomplished by merely terminating the upper edges of the flap 4 and reinforcing bands 12 and 13 along the same line, adapted to correspond with the upper edge of the shelf, as exhibited in this figure.

All of the shelf papers which I have shown in the preceding figures may be adapted for edgings in the same manner as Figure 10 illustrates the modification of Figure 5. However, if a finished or further reinforced upper edge of an edging is desired, the uppermost reinforcing band 21 which corresponds to the band 13 of Figure 10 may be extended upwardly over the upper edges of the band 12 and the flap 4 and thence downwardly over the rear face of the flap 4 and adhesively secured thereto as shown in Figure 11. This arrangement will produce a structure similar to Figure 10, but with a finished upper edge, which is unusually rigid for a paper shelf edging. If still more rigidity is desired, the upper edge of the flap 4 may be returned upon itself and adhesively secured in position as shown in Figure 12, the reinforcing bands being of any desired shape and contour at the free edges. The mode of strengthening and further stiffening the upper edges, as exhibited in Figures 11 and 12, may be carried out in connection with any other edging made in accordance with the structure of the several preceding figures.

No attempt has been made to show all of the various modifications of which this invention is susceptible, either in connection with the shelf paper and edging combination or with the edging per se, but the showing made is sufficiently illustrative to show various adaptations and embodiments of which this invention is susceptible. In practically carrying out the invention, the reinforcing bands may be made of different colors than the flaps with which they are associated, and their edges may be shaped to give the desired contours. Likewise, the various parts of the edgings may be embossed or perforated as shown, for example, in Figure 2, or they may be printed in different colors. Similarly said reinforcing bands in certain cases may, if desired, be transversely pleated as the bands 16 are shown in Figure 7 to produce new and attractive designs of a highly æsthetic and ornamental character, all without prohibitive increase in cost of production and to very marked advantage in the finished product from the standpoint of wear and appearance.

From the foregoing description, it will be apparent that the invention produces marked improvements in shelf paper edgings either with or without shelf covering extensions, and consists, essentially, in the utilization of one or more longitudinally extending reinforcing bands which preferably extend parallel to the line of symmetry of the free edge of the edging or the shelf on which the edging is to be used and which parts are adhesively secured for the whole or a part of their respective widths to one another, in such manner as to produce a structure which is, at least in part, laminated in order to obtain longi-

tudinal stiffness of the desired character with attendant reinforcement against transverse tearing of the edging.

The invention is to be understood as not limited to the detailed showing of the drawings, but is to be construed as fully commensurate with the appended claims.

In the foregoing detailed description and in the appended claims, I have referred to 10 that portion of the shelf paper which overlies or rests upon the upper surface of the shelf as a "shelf covering portion". This shelf covering portion may have a width substantially equal to or less than the width of the 15 shelf, but in any event, it covers at least a portion of the width of the shelf.

Having thus fully described the invention, what I claim as new and desire to secure by Letters Patent is:

20 1. A shelf paper comprising a paper shelf covering portion, a longitudinal margin of which is extended to hang over the edge of a shelf as a flap, and at least one reinforcing band extending longitudinally of and adhesively secured to the flap for reinforcement of said flap and at least a portion of which band is visible to an observer from the front edge of a shelf when the shelf paper is positioned thereon.

25 2. A shelf paper comprising a paper shelf covering portion, a longitudinal margin of which is extended to hang over the edge of a shelf as a flap, and a reinforcing band extending longitudinally of and adhesively secured to the flap for the full depth of the latter for reinforcement of said flap and at least a portion of which band is visible to an observer from the front edge of a shelf when the shelf paper is positioned thereon.

30 3. A shelf paper comprising a paper shelf covering portion, a longitudinal margin of which is extended to hang over the edge of a shelf as a flap, and a reinforcing band extending longitudinally of and adhesively secured to the flap to reinforce said flap and at least a portion of which band is visible to an observer from the front edge of a shelf when the shelf paper is positioned thereon, said reinforcing band extending transversely beyond the flap and over the margin of the shelf covering portion to reinforce that portion of the shelf paper adapted to overlie the edge of the shelf.

35 4. A shelf paper comprising a paper shelf covering portion, a longitudinal margin of which is extended to hang over the edge of a shelf as a flap, and at least one reinforcing band extending continuously longitudinally of and adhesively secured to the front face of the flap for reinforcement of said flap.

40 5. A shelf paper comprising a paper shelf covering portion, a longitudinal margin of which is extended to hang over the edge of a shelf as a flap, and a reinforcing band extending continuously longitudinally of and

adhesively secured to the back face of the flap for reinforcement of said flap and extending below the free edge of the flap to be visible to an observer from the front edge of a shelf when the shelf paper is positioned thereon.

6. A shelf paper comprising a paper shelf covering portion, a longitudinal margin of which is extended to hang over the edge of a shelf as a flap, and a reinforcing band extending uninterruptedly longitudinally of said flap and adhesively secured to the back face of and for substantially the full length of said flap to produce a longitudinally reinforced and stiffened flap.

7. A shelf paper comprising a paper shelf covering portion, a longitudinal margin of which is extended to hang over the edge of a shelf as a flap, and a plurality of reinforcing bands mounted on the flap in overlapping positions, to be visible to an observer from the front of the shelf when the shelf paper is positioned thereon, and adhesively secured in place for reinforcement of the flap portion.

8. A paper shelf edging embodying a longitudinally extending foundation strip of paper, and a separate supplementary reinforcing band, of lesser width than the width of the foundation strip, extending continuously along and adhesively secured to the foundation strip for reinforcement, to be visible to an observer, from the front edge of a shelf when the edging is positioned thereon, whereby a stiffened edging is produced by adhesively uniting a plurality of plies.

9. A paper shelf edging embodying a longitudinally extending foundation strip of paper, and a plurality of separate supplementary reinforcing bands, of lesser width than the width of the foundation strip, extending continuously along and adhesively secured to the front face of the foundation strip for reinforcement, to be visible to an observer from the front edge of a shelf when the edging is positioned thereon, whereby a stiffened edging is produced by adhesively uniting a plurality of plies.

In testimony whereof, I have signed the foregoing specification.

EDWARD KARFIOL.
